ATTORNEY.

UNITED STATES PATENT OFFICE.

JOHN T. HAYNE, OF DETROIT, MICHIGAN.

RUNNING-BOARD FOR AUTOMOBILES.

1,382,507.

Specification of Letters Patent. Patented June 21, 1921.

Application filed May 3, 1920. Serial No. 378,690.

To all whom it may concern:

Be it known that I, JOHN T. HAYNE, a citizen of the United States, residing at Detroit, in the county of Wayne and State of Michigan, have invented certain new and useful Improvements in Running-Boards for Automobiles, of which the following is a specification.

This invention relates to a device for 10 clamping or securing automobile running boards in fixed position, and pertains especially to running board construction and an interlocking device having such peculiar construction as to permit a tread sheet of 15 linoleum or rubber, or similar material, to be applied to such boards without having the device interfere with such application and without exposing any part of the device through or on the tread surface of the 20 tread sheet.

The object of the invention is to provide a device of such novel and peculiar shape and construction as to lock itself against turning in a permanently mat-covered running board while the board is being secured 25 to the board frame of an automobile, and as to be confined within the board so as to leave the face of the board, to which a tread mat is molded, free from obstructions and 30 without defacement either to the board or the mat.

A further object of the invention is to provide a novel and peculiar device comprising 35 a nut member having such construction as to afford a flaring flanged head, and means for preventing the nut from turning during the screwing thereinto of a clamping or set bolt.

Other advantages and improved results 40 are attainable in the manufacture and practical application of the invention as will hereinafter appear.

In the accompanying drawings forming part of this application:—

Figure 1 is a perspective view of part of 45 a running board and frame showing the tread mat partly broken away and showing the application of the invention.

Fig. 2 is a cross section of a running board 50 and tread mat secured to the board frame by a set of my improved fasteners.

Fig. 3 is a perspective view of one of the complete devices.

Fig. 4 is a cross section of a running board 55 and part of its supporting frame showing a modification of the invention.

The same reference characters denote the same parts throughout the several views of the drawings.

The invention being intended especially 60 to permit rubber, linoleum or other tread mats to be secured to running boards without puncturing or otherwise making holes or countersinks in the mat for bolts, nuts or similar devices commonly used for securing the board to the board frame or supports, and to permit adhesion of the mats to the boards or to a metal plate covering the board, so that the meeting surfaces of 70 the mat and the board may be free of obstruction and interference by using my improved board securing device.

In carrying out my invention I employ a metal stud, preferably of less length than the thickness of a running board as 1, which 75 has holes 2 extending therethrough with a countersunk end in the upper face of the board, and said holes are provided with a pair of vertical grooves 3. The board has other holes or cavities 4, into which are 80 pressed lugs or projection 5 of the tread mat 6 having tread ribs 7. The side edges of the board are reduced in thickness from that of the body of the board so as to form a seat 8 for the thickened side edges of the 85 mat as at 9, and the parts 9 together with the lugs 5 are molded, by high pressure, onto the upper face of the board, with the body of the mat covering said countersunk holes of the board, but this operation is 90 preceded by inserting into the holes 2 of the board, from the upper face thereof, a stud, now to be particularly described.

The stud comprises a cylindrical body 10, preferably of such length as not to extend 95 entirely through the board holes 2, and has a central screw socket 11 closed at the upper end by a spherical head 12 forming an annular flange 13 projecting laterally from the body 10, and extending over and beyond 100 a pair of opposite cleats or locking members 14 formed on the outer face of the body 10 and extending from said flange 13 to the bottom end of said body. Obviously when 105 the stud is inserted into the stud holes 2 from the upper face of the board, the stud head with its flange fits within the board countersunk holes 2 and the cleats 14 fit the grooves 3 for locking the stud in position against turning. The mat is then 110 pressed into position upon the board so as to be fixed therewith, and prevents displace-

ment of the studs, thus forming a complete mat tread covered running board ready for transportation and application to the running board frame or supports 15 of an automobile.

The mat covered board is attached to the frame or supports 15 by means of a set bolt 16 extending through said supports and into the screw socket 11 of the stud with a washer 17 therebetween. Obviously the bolt is of less length than the depth of the socket 11, so as to utilize the take up space between the lower or open end of this stud and the lower or under face of the board for clamping various thicknesses and tightening the boards as occasion may demand.

Referring to the modification shown in Fig. 4 of the drawings, the heads of the studs 18 are brazed or spot welded in countersinks 19 of a thin metal plate 20 having holes into which lugs 21 of the composition mat 22 enter when this mat is pressed onto the plate 20. This arrangement permits the plate and the studs to be handled as one article and applied to various running boards as 23 after the stud holes are made therein to correspond with the studs.

Having thus described my invention what I claim as new and desire to secure by Letters Patent is:—

1. A running board for automobiles, in-

cluding a main member having a plurality of countersunk stud-receiving orifices whose walls are provided with longitudinal grooves, studs received by said countersunk orifices, each stud having a screw-threaded socket, an end flange and lateral longitudinal cleats, a tread-mat member, and securing means between said studs and the running board threaded into the sockets of said studs, said grooves receiving said longitudinal cleats, the end flanges of said studs being received by the countersinks of said orifices.

2. In running boards for automobiles, a main board, a board plate having a plurality of mat holes and a plurality of countersunk stud holes corresponding with like holes in the main board, studs each having a screw threaded socket and a head attached in the countersink of said plate, said studs extending through the plate and into the main board, and bolts fitting the screw sockets for clamping the said plate and the main board to running board supports.

In witness whereof I hereunto set my hand in the presence of two witnesses.

JOHN T. HAYNE.
